UNITED STATES PATENT OFFICE

115,060

DESIGN FOR A COMBINED WATCHCASE AND LOCKET

William C. Barthman, New York, N. Y.

Application August 1, 1938, Serial No. 79,019

Term of patent 7 years

To all whom it may concern:

Be it known that I, William C. Barthman, a citizen of the United States, residing at New York, in the county of New York and State of New York, have invented a certain new, original, and ornamental Design for a Combined Watchcase and Locket, of which the following is a specification, reference being had to the accompanying drawing, forming a part thereof.

What is claimed is:

The ornamental design for a combined watchcase and locket, as shown and described.

WILLIAM C. BARTHMAN.
